UNITED STATES PATENT OFFICE.

CHARLES E. JACKSON, OF ROCKFORD, ILLINOIS.

CORN-PLANTER.

SPECIFICATION forming part of Letters Patent No. 620,710, dated March 7, 1899.

Application filed January 17, 1898. Serial No. 666,902. (No model.)

To all whom it may concern:

Be it known that I, CHARLES E. JACKSON, a citizen of the United States, residing at Rockford, in the county of Winnebago and State of Illinois, have invented certain new and useful Improvements in Corn-Planters, of which the following is a specification.

The object of this invention is to produce an accurate practical self-checking corn-planter. To accomplish this result, I have employed the ordinary planter-frame and its supporting-wheels, but have supplied mechanism by which the power necessary to move the dropping valves or slides is furnished by the supporting-wheels and stored in suitable springs, and the force thus reserved is released to operate the checking-slide by devices on an endless measuring-chain, which spreads itself upon the surface of the ground underneath the planter-frame as the latter travels over the field. Prongs at regular intervals extending from certain of the links of this endless chain enter the soil and not only aid in preventing that portion of the chain which lies in contact with the ground from slipping or moving with relation thereto, but makes marks thereon to indicate the position of the corn-hills for a purpose to be hereinafter explained. By increasing or diminishing the number of releasing devices on the measuring-chain the frequency of the corn-hills is varied.

In the drawings, Figure 1 is a side elevation of a corn-planter embodying the features of my invention, certain parts being removed to show the operative mechanism. Fig. 2 is a plan view of the planter. Fig. 3 is a skeleton plan view illustrating the marker and the manner of its attachment to the planter-frame. Fig. 4 is a fragmental view of the releasing device for the checking mechanism. Fig. 5 is an edge view of the sprocket-wheel shown in the preceding figure to illustrate the roller-bearing tripping-link. Fig. 6 is a perspective view of one of the pronged links for the endless measuring-chain. Fig. 7 is a view of the checking-bar and its detent. Fig. 8 is an enlarged plan view of the mechanism for storing power to actuate the checking-bar of the corn-planter.

Like letters of reference indicate corresponding parts throughout the several views.

A is the main frame of the corn-planter,

A' is the axle therefor, and A² are the supporting-wheels. These wheels have a ratchet connection of common form with the axle so arranged that either or both will drive the axle when the planter is moved forward and will slip thereon when turned backward. The planter-frame is jointed at A³, as is usual in planters of this form. 55

B and B' are two endless chains and their supporting sprocket-wheels for transmitting power from the axle A' to the shaft B², journaled in the main frame A. This shaft is rotated constantly in one direction during the forward travel of the planter. 60

B³ and B⁴ are bevel-gears, facing one another, loosely mounted on the shaft B².

B⁵ is a clutch-collar arranged to rotate with the shaft B², but having an endwise movement to permit of its engagement with one or the other of the bevel-gears B³ B⁴, thereby imparting the motion of the shaft B² to the bevel-gear with which the clutch B⁵ is in engagement. 70

C is a shifting-lever for the clutch-collar B⁵, having the pivot C' in the curving arm C² rigidly fixed to the checking-bar, which extends between the corn-boxes of the planter. 75

C³ are arms rigidly mounted on and projecting forwardly from the curving arm C².

D is a shaft journaled in the main frame A, extending at right angles to the shaft B².

D' is a bevel-gear fixed on the shaft D, having an engagement with both of the gears B³ B⁴. 80

D² is a bevel-gear also fixed on the shaft D.

E is a screw-threaded shaft extending parallel with the line of the shaft B², journaled in the main frame A. The bevel-gear E' is rigidly mounted on the shaft E and meshes with the gear D². 90

E² is a nut adapted to travel on the screw-threads of the shaft E, while the guide-rod E³ prevents the nut from turning with the shaft E. 95

E⁴ is a pin projecting upward from the nut E².

It will be seen from the foregoing that the screw-shaft E is capable of rotation in either direction, such direction depending upon the engagement of one or the other of the bevel-gears B³ B⁴ by the clutch-collar B⁵. 100

H is a spring-actuated detent or plunger

capable of a slight vertical movement. H' is a bracket therefor.

H² is the plunger-spring, lying between the upper part of the bracket H' and the pin H³, extending through the detent or plunger H. The plunger extends through an opening in the main frame A and into one of two openings G⁶ in the checking-bar G, one or the other of which openings coincides with the spring-10 plunger H when the checking-bar G is thrown to the extremity of its movement in either direction.

H⁴ is a flexible lifting-arm, and H⁵ a rod rigidly secured thereto, which rod is provided with the antifriction-roller H⁶, by means of which arm and rod the plunger H is lifted against the action of the spring H² out of the opening G⁶ in the checking-bar G, with which the plunger is in engagement.

20 The foregoing describes the mechanism whereby the power for operating the checking-slides and dropping the corn in the hills is stored in the springs G⁴ G⁵. Its operation is as follows: Motion from the supporting-wheels is transmitted to the shaft B² by the endless-chain gearing B and B' and is further communicated to the screw-threaded shaft E by the intermediate shaft D and the bevel-gears D' D², fixed thereon. The direction of 25 the rotation of the screw-threaded shaft E, however, depends upon which one of the bevel-gears B³ B⁴ is engaged by the clutch-collar B⁵ of the shaft B². As the screw-threaded shaft E is rotated the nut E² thereon is fed along the guide-rod E³, and one or the other of the springs G⁴ G⁵ is extended by reason of the connection between the spring and the nut E². When the pin E⁴ has traveled the length of the slotted opening F' in the bar 30 F, it commences to move the said bar, turning the shifting-lever C upon its pivot C' and distending one of the coil-springs F³. When the shifting-lever C has been moved a certain distance, the clutch-collar B⁵ is withdrawn from its engagement with either of the bevel-gears B³ B⁴, and motion from the supporting-wheels is not communicated farther than the shaft B². By this action of the mechanism the checking-bar G is held at one of 35 the extremes of its throw by the engagement of one of the openings G⁶ therein by the plunger H against the tension of one of the springs G⁴ or G⁵ and ready to be released to the action of the said spring when the proper time arrives.

J is an endless chain belt constituting the measuring-chain, the lower side of which lies in contact with the ground. It has several pronged links J' for engaging with the soil 40 to prevent the dragging of the chain over the surface thereof and for marking the location of the corn-hills.

J², J³, J⁴, J⁵, and J⁶ are idler sprocket-wheels rotatably mounted in the framework J⁷ for 45 supporting the measuring-chain J.

J⁸ is a shoe for clearing a path for the measuring-chain J. It has a pivotal connection

at J⁹ with the framework J⁷ and an adjustable connection J¹⁰ with the lifting-bar J¹¹.

J¹² is a bracket for the support of the lifting-bar J¹¹, and J¹³ is a lifting-lever for adjusting the height of the lifting-bar J¹¹ and the shoe J⁸.

J¹⁴ is a roller-link, it being similar to the other links of the measuring-chain J, excepting that it provides a pivot for the reception of an antifriction-roller J¹⁵ and has an arm J¹⁶ for bearing against the side of the sprocket-wheel to prevent the link from turning when the roller J¹⁵ engages the roller H⁶.

When the planter moves forward, the measuring-chain runs idly upon its supporting sprocket-wheels, its lower side lying stationary upon the ground. Provision is made by slotted openings in the sides of the framework 85 J⁷ to alter its length and to adjust the position of the links J' and J¹⁴.

K is a sector lifting-lever.

K' is a coil-spring intervening between the lower arm of the lever K and a point on the 90 forward portion of the main frame for raising the latter from the ground and carrying the weight thereof upon the supporting-wheels A². The foot-brackets K² and their supporting-bar K⁸ form a part of the lever K and are 95 to assist in the operation thereof.

L is a sector lifting-lever, its purpose being to raise bodily the measuring-chain and the entire mechanism having connection therewith by means of the link L'.

M is a seat for the operator, and M' are seat-supports. M² and M³ are eyes or loops in one of these supports.

N is a marker for indicating the driving-line across the field. N' is the supporting-arm therefor, having a swivel connection with the rear part of the main frame.

N² is a shifting-rod for the marker, having a hook connection with the eye M². The shifting-rod extends obliquely forward from the 110 eye, resting in one of the two forked brackets O' at either side of the main frame A.

N³ is a cord for connecting the outer end of the shifting-rod N' with the outer end of the marker-arm.

To shift the marker after turning the planter, as at the end of a row, the operator lifts the shifting-bar N², and the marker-arm readily swings about to the opposite side of the machine, turning in its swivel connection 120 with the main frame A.

N⁴ is a sheave loosely hung under the operator's seat M.

N⁵ is a chain connecting the rear end of the arm K³ of the lever K with the marker-arm, 125 passing intermediately over the sheave N⁴. This latter connection causes the marker-arm to be raised whenever the forward portion of the planter is lifted as in turning.

O is the setting-bar, by means of which the 130 planter may be started, so as to plant the hills of corn in transverse rows. It has the bearing-brackets O', in which it is free to slide, and the arms O², extending downward from

either end of the bar O. A cord O³ extends from end to end of this bar, passing through openings in the brackets O' and the eye M³ to be within reach of the operator.

5 O⁴ are two notched brackets for receiving the arms O² and holding them in a vertical position. The parts of the mechanism are relatively so arranged that when the arm O², thrown outward as far as possible from the 10 side of the planter, is directly over the mark made in the ground by one of the pronged links J' of the measuring-chain J and the roller-link J¹⁴ is just leaving the sprocket J⁶ the checking mechanism will drop a hill of 15 corn transversely opposite the hill on the next adjacent row.

In starting the planter in the field the marker is set on the proper side of the machine, the measuring-chain and its frame- 20 work are lowered by the lever L, so that their weight rests upon the ground, the forward part of the main frame is likewise adjusted by means of the lever K, and the planter started forward. As the axle A' rotates the 25 endless chains B and B' and the shaft B² are driven. The clutch-collar B⁵, rotating constantly with the shaft B², will probably be in engagement with one of the bevel-gears B³ B⁴, I will say, for purposes of illustration, 30 with the former, which will then be driven with the shaft B². Motion will thus be communicated through the shaft D and its bevel-gears to the screw-threaded shaft E, which will be rotated in such a direction that the 35 nut E² will travel thereon from left to right as the planter faces, and tension will be given to the spring G⁴.

The pin E¹ on the nut E² travels the length of the slotted opening F' in the bar F, and 40 continuing in its movement forces the said bar lengthwise in the same direction. The bar F has a pivotal connection with the shifting-lever C, and the latter has a connection with and moves the clutch-collar B⁵ length- 45 wise of the shaft B², so that when the rod F is moved a little distance the lever C is oscillated on its pivot C' and the clutch-collar B⁵ withdrawn from engagement with the gear B³. The tension of the spring G⁴ now tends 50 to draw the checking-bar G from left to right, but the bar is retained in position by the plunger-rod H.

When the measuring-chain J is rotated sufficiently to bring the roller J¹⁵ of the link J¹⁴ 55 into engagement with the roller H⁶, the plunger-rod H is raised from the opening G⁶ in the checking-bar G, and the spring G⁴ quickly draws the latter bar to the opposite extremity of its throw, where it is held by the plunger 60 H entering the other opening G⁶ of the bar. The curving bracket C² being rigidly mounted on the checking-bar G is also moved toward the right by the reciprocation of the bar a sufficient distance to cause the clutch-collar 65 B⁵ to engage the bevel-gear B⁴. Continued motion of the shaft B² causes the screw-threaded shaft E to be again rotated, but in the

opposite direction, whereby the movement of the nut E² will impart tension to the spring G⁵, and thus prepare for an opposite move- 70 ment of the checking-bar G. When the proper tension has been given to the spring G⁵, the lever C is moved to such a position that the clutch-collar B⁵ rotates intermediate the gears B³ B⁴ without engaging either until 75 the checking-bar G is tripped by the roller J¹⁵ of the link J¹⁴. The mechanism may be "geared up" sufficiently that the travel of only a few inches of the planter upon the ground will set the parts for "checking." 80

The frequency of the checking is governed by the number of roller-links J¹⁵ in the chain, and this number may be altered to suit the requirements of the occasion. The length of the measuring-chain may also be varied, provision for this adjustment being made in the slotted openings in the framework J⁷. When the end of the row is reached, the forward part of the planter is raised for turning, which also raises the marker from the ground and 90 the measuring-chain and its frame. When the planter has been turned, the marker is thrown to the opposite side of the machine by the rod N² without necessitating the operator leaving his seat, the machine moved 95 so that the arm O² of the setting-bar O stands just over one of the marks made by a pronged link in the measuring-chain between the two next rows, the measuring-chain adjusted so that one of the roller-links J¹⁴ will be just 100 leaving the sprocket J⁶, the lever K thrown forward to lower the mechanism to the ground, and the planter started across the field. The measuring-chain may be set at any desirable height by the lever L; but no movement of 105 the lever will cause a movement of the chain upon its supporting-sprockets, so as to move the tripping device, inasmuch as the frame J⁷ is jointed at its forward end and has a compensating movement when the lever L is 110 moved, always remaining at substantially the same tension.

When it is desirable to raise or lower the runner J⁸ and the forward end of the frame J⁷, it may be accomplished by operating the 115 lever J¹³.

I claim as my invention—

1. In a corn-planter, in combination, a main frame, a seed-receptacle, a seed-dropping device, a spring for storing power to actuate the 120 seed-dropping device, a detent for the dropping device and a release for said detent, substantially as and for the purpose specified.

2. In a corn-planter, in combination, a main frame, a seed-receptacle, a seed-dropping device, a detent therefor, a spring for actuating the seed-dropping device, means for imparting power to said spring, and a release for the detent, substantially as and for the purpose specified. 125

3. In a corn-planter, in combination, a main frame, supporting-wheels therefor, a seed-receptacle, a seed-dropping device, a detent therefor, a spring for actuating the seed-drop- 130

ping device, a connection between the said spring and the supporting-wheels for imparting power to the spring, and a release for the detent, substantially as and for the purpose specified.

4. In a corn-planter, in combination, a main frame, supporting-wheels therefor, a seed-receptacle, a seed-dropping device, a detent therefor, a spring for actuating the seed-dropping device, a screw-threaded shaft, a nut on the shaft, means for rotating the screw-threaded shaft, a connection between the spring and the nut, and a release for the detent, substantially as and for the purpose specified.

5. In a corn-planter, in combination, a main frame, supporting-wheels therefor, a seed-receptacle, a seed-dropping device, a detent therefor, a spring for actuating the seed-dropping device, a connection between the spring and the supporting-wheels for imparting tension to the spring, and a release for the detent, substantially as and for the purpose specified.

6. In a corn-planter, in combination, a main frame, a rotatable axle for the frame, supporting-wheels mounted on the axle and having a ratchet connection therewith, a seed-receptacle, a seed-dropping device, means for storing power to actuate the seed-dropping device, a detent for the dropping device, and a release for said detent, substantially as and for the purpose specified.

7. In a corn-planter, in combination, a main frame, a rotatable axle for the frame, supporting-wheels mounted on the axle, and having a ratchet connection therewith, a seed-receptacle, a seed-dropping device, a detent for the dropping device, a spring for actuating the dropping device, a screw-threaded shaft for imparting power to the said spring, which shaft has a connection with the rotatable axle, and a release for the detent, substantially as and for the purpose specified.

8. In a corn-planter, in combination, a main frame, a rotatable axle for the frame, supporting-wheels mounted on the axle and having a ratchet connection therewith, a seed-receptacle, a seed-dropping device, a detent for the dropping device, a spring for actuating the dropping device, a screw-threaded shaft, a nut thereon having a connection with the said spring, means for communicating motion from the rotatable axle to the screw-threaded shaft, and a releasing device for the detent, substantially as and for the purpose specified.

9. In a corn-planter, in combination, a main frame, a rotatable axle, supporting-wheels on the axle, a seed-receptacle, a seed-dropping valve, a rod and a detent for said valve, a spring for actuating the valve to drop, a screw-threaded shaft capable of being rotated by a connection with the axle, a nut on the shaft for giving tension to the spring, and a releasing device for the detent, substantially as and for the purpose specified.

10. In a corn - planter, in combination, a main frame, a rotatable axle, supporting-

wheels on the axle, a seed - receptacle, two seed - dropping valves, a rod between the valves, a detent for the valves, a rotatable screw-threaded shaft, a nut on the shaft, two springs having a connection with the nut and the rod, a bracket affixed to the rod, a shifting-lever for changing the direction of the rotation of the screw-threaded shaft, pivoted in the bracket, a connection between the nut and the shifting-lever, and a releasing device for the detent, substantially as and for the purpose specified.

11. In a corn - planter, in combination, a main frame, a rotatable axle, supporting-wheels on the axle, two seed-receptacles, two seed - dropping valves, a rod extending between the valves, a detent for the valves, a rotatable screw-threaded shaft, a nut on the shaft, two springs attached to the valve-rod and having a connection with the nut, a shaft mounted in the main frame and having a rotatable connection with the axle, two bevel-gears loosely mounted on the last-named shaft, a clutch between the gears capable of engaging either one with the shaft, a bracket affixed to the valve-rod, a shifting - lever pivotally mounted on said bracket, and having an engagement with said clutch, an arm having a pivotal engagement with the nut and the shifting-lever, and a releasing device for the detent, substantially as and for the purpose specified.

12. In a corn - planter, in combination, a main frame, a rotatable axle, supporting-wheels on the axle, two seed-receptacles, two seed - dropping valves, a rod extending between the valves, a detent for the valves, a rotatable screw-threaded shaft, a nut on the shaft, two springs attached to the valve-rod and having a connection with the nut, a shaft rotatably mounted in the main frame, a driving connection between the axle and the last-mentioned shaft, two bevel - gears loosely mounted on the shaft, a clutch for engaging either of said gears with the shaft, a gear connection between the bevel-gears and the screw-threaded shaft for rotating the latter, a bracket fixed to the valve-rod, a shifting-lever for operating the clutch pivotally mounted on said bracket, an arm extending from the nut to the said shifting-lever and having a pivotal connection with both the nut and the lever, and a releasing device for the detent, substantially as and for the purpose specified.

13. In a corn - planter, in combination, a main frame, a rotatable axle, supporting-wheels on the axle, two seed-receptacles, two seed-dropping valves, a rod extending between the valves, a detent for the valves, a rotatable screw-threaded shaft, a nut on the shaft, two springs attached to the valve-rod and having a connection with the nut, a shaft rotatably mounted in the main frame, a driving connection between the axle and the last-mentioned shaft, two bevel - gears loosely mounted on the shaft, a clutch for engaging

- either of said gears with the shaft, a gear connection between the bevel-gears and the screw-threaded shaft for rotating the latter, a bracket fixed to the valve-rod, two arms projecting from the bracket, a shifting-lever for operating the clutch, pivotally mounted on said bracket, an arm extending from the nut to the said shifting-lever and having a pivotal connection with both the nut and the lever, a spring extending between each of the arms on the bracket and the arm pivoted to the shifting-lever, and a releasing device for the detent, substantially as and for the purpose specified.
14. In a corn - planter, in combination, a main frame, a seed-receptacle, a seed-dropping device, a detent for the dropping device and a releasing device for said detent, substantially as and for the purpose specified.
15. In a corn - planter, in combination, a main frame, a seed-receptacle, a seed-dropping device, means for storing power, to actuate the seed-dropping device, a detent for the dropping device, and a revolving releasing device for said detent, substantially as and for the purpose specified.
16. In a corn - planter, in combination, a main frame, a seed-receptacle, a seed-dropping device, means for storing power to actuate the seed-dropping device, a detent for the dropping device, and an endless measuring-belt for releasing the detent, substantially as and for the purpose specified.
17. In a corn - planter, in combination, a main frame, a seed-receptacle, a seed-dropping device, means for storing power to actuate the seed-dropping device, a detent for the dropping device, a sprocket-wheel, an endless measuring-chain one of the links of which has a projecting pivot and a bracket-arm for extending by the side of the sprocket-wheel, and a roller mounted upon the pivot, substantially as and for the purpose specified.
18. In a corn - planter, in combination, a main frame, a seed-receptacle, a seed-dropping device, means for storing power to actuate the seed-dropping device, a detent for the dropping device, and an endless measuring-chain having projections extending therefrom for releasing the detent, substantially as and for the purpose specified.
19. In a corn - planter, in combination, a main frame, a seed-receptacle, a seed-dropping device, means for storing power to actuate the seed-dropping device, a detent for the dropping device, an endless chain belt, sprocket-wheels therefor, one of the links of said belt having a projection for releasing the detent, substantially as and for the purpose specified.
20. In a corn - planter, in combination, a main frame, a seed-receptacle, a seed-dropping device, means for storing power, to actuate the seed-dropping device, a detent for the dropping device, an endless measuring-chain, a supporting - frame for the chain, sprockets for the chain, journaled in the frame, one of the links of said belt having a projection for releasing the detent, and means for raising bodily the supporting-frame for the measuring-chain, substantially as and for the purpose specified.
21. In a corn - planter, in combination, a main frame, a seed-receptacle, a seed-dropping device, means for storing power to actuate the seed-dropping device, a detent for the dropping device, an endless measuring-chain, a supporting-frame for the chain, having a jointed compensating portion, a shoe pivoted to the frame, a lifting-lever for the shoe and the forward end of the said frame, and a lever for lifting the frame bodily, substantially as and for the purpose specified.
22. In a corn - planter, in combination, a main frame, a rotatable axle journaled therein, supporting-wheels on the axle, having a ratchet connection therewith, a seed-receptacle, a seed-dropping device, means for storing power to actuate the seed-dropping device, a detent for the seed-dropping device, and a release for said detent, substantially as and for the purpose specified.
23. In a corn - planter, in combination, a main frame, supporting-wheels therefor, a corn-planting device, a marker-arm, a marker on the arm, a rod extending obliquely forward from the main frame, and a flexible connection between the marker-arm and the rod, substantially as and for the purpose specified.
24. In a corn - planter, in combination, a main frame, supporting-wheels therefor, a corn-planting device, a marker-arm, having a swivel connection with the main frame, a marker on the arm, a rod extending obliquely forward from the main frame, and a flexible connection between the rod and the marker-arm, substantially as and for the purpose specified.
25. In a corn - planter, in combination, a main frame, supporting-wheels therefor, a corn-planting device, a device for making a mark in the ground between the corn-hills as they are planted, a bracket on the main frame, a sliding rod therein, an arm near the end of the sliding rod and a shifting-cord for sliding the rod in its bracket from one side of the planter to the other, and a bracket for holding the arm upright when the rod is shifted to either side of the planter, substantially as and for the purpose specified.

CHARLES E. JACKSON.
